DESIGN FOR A SHOE RACK

Irving Seltzer, Brooklyn, N. Y.

Application August 17, 1940, Serial No. 94,481

Term of patent 7 years

To all whom it may concern:

Be it known that I, Irving Seltzer, a citizen of the United States, residing at Brooklyn, in the county of Kings and State of New York, have invented a new, original, and ornamental Design for a Shoe Rack, of which the following is a specification, reference being had to the accompanying drawing, forming part thereof.

I claim:

The ornamental design for a shoe rack, as shown.

IRVING SELTZER.
